N. S. Hie

Attorney

UNITED STATES PATENT OFFICE.

EARL DENNY, OF ONTARIO, CALIFORNIA.

POISON-BOTTLE GUARD.

1,176,351.

Specification of Letters Patent. Patented Mar. 21, 1916.

Application filed October 28, 1915. Serial No. 58,410.

To all whom it may concern:

Be it known that I, EARL DENNY, a citizen of the United States, residing at Ontario, in the county of San Bernardino, 5 State of California, have invented a new and useful Poison-Bottle Guard; and I do hereby declare the following to be a full, clear, and exact description of the invention, such as will enable others skilled in 10 the art to which it appertains to make and use the same.

The present invention relates to a poison bottle guard indicator, and has for its object to provide a device of this character 15 which can be readily applied as an attachment to bottles of the conventional construction and which will prevent the cork from being withdrawn by children, or even by adults without warning being given that the 20 contents of the bottle are of a poisonous or dangerous nature.

Further objects of the invention are to provide a poison bottle guard which is simple and inexpensive in its construction, 25 which can be readily applied to the bottle, which can be made sufficiently strong to prevent the withdrawal of the stopper by children, and which when handled in the dark will give warning that the bottle contains a 30 poison, thereby preventing possible confusion between a poison bottle and a bottle whose contents are harmless.

With these and other objects in view, the invention consists in certain novel combinations and arrangements of the parts as will 35 more fully appear as the description proceeds, the novel features thereof being pointed out in the appended claim.

For a full understanding of the invention, 40 reference is to be had to the following description and accompanying drawing, in which:—

Figure 1 is a side elevation of a bottle neck and stopper, showing a guard constructed in accordance with the invention 45 applied thereto, portions of the bottle neck and stopper and the upper end of the guard, being broken away and shown in section. Fig. 2 is a top plan view thereof. Fig. 3

50 is a detail perspective view of the guard removed from the bottle neck. Fig. 4 is a side elevation of a bottle neck showing a modified form of the guard applied thereto. Fig. 5 is a view similar to Fig. 4, showing 55 a still further modified construction of

guard. Fig. 6 is a side elevation of the modification shown by Fig. 5, viewed at a position at right angles to that of Fig. 5.

Corresponding and like parts are referred to in the following description and indicated in all the views of the drawing by the same reference characters.

For the purpose of illustration the invention is shown as applied to a bottle A provided with a neck 1 having a stopper 2 fitted 65 in the mouth thereof, the outer end of the neck being provided with the usual exterior rim or rib 3. The guard includes a spring clip 4 formed with opposed spring arms 4^a adapted to spring around the bottle neck and 70 retain the guard in position thereon. Projecting upwardly from the back of the clip 4 is a stock 5 which extends along the side of the bottle neck when the device is in position, an intermediate portion of the stock being 75 offset outwardly as indicated at 5^a to provide a shoulder which fits against and engages the rim 3 at the mouth of the bottle to prevent the clip 4 from sliding outwardly upon the bottle neck. Integral with 80 the upper end of the stock 5 is a spring finger 6 which extends across the top of the stopper 2 to retain the same in position within the bottle neck and prevent withdrawal thereof. The extremity of the spring finger 85 6 may be provided with a downwardly extending lip 6^a to engage a side of the projecting end of the stopper and coöperate with the clip to hold the device in position. If desired, the spring finger 6 may have a 90 pair of prongs or teeth 7 stamped therefrom and bent inwardly so as to bite into the top of the stopper 2 and anchor the device in position.

The guard may be formed of stiff spring 95 metal and made sufficiently strong so that it can not be removed by a small child, and the presence of the guard would serve to warn an adult of the poisonous nature of the contents of the bottle. However, by springing 100 the finger 6 upwardly and forcibly withdrawing the spring clip 4 from the bottle neck the guard can be removed from the bottle and the stopper 6 withdrawn.

A slight modification is shown by Fig. 4, 105 in which the spring clip 4 and spring finger 6 are provided at the edges thereof with integral outwardly projecting teeth 8, said teeth not being sufficiently sharp to cut or injure the fingers when manipulating the 110

guard, although the presence thereof would serve to emphasize the dangerous character of the contents of the bottle, and render impossible a mistake when taking medicine in 5 the dark.

A further modification is shown by Figs. 5 and 6, in which the end of the spring finger 6 is provided with a downwardly projecting extension 9 having a slot 9^a therein 10 adapted to receive out turned extremities 10 provided at the ends of the arms 4^a of the clip 4. These outwardly projecting extremities 10 may have corresponding openings 15 therein to receive a locking member such as the shackle of a small padlock 11, and with such a construction it would be impossible for any person to obtain access to the contents of the bottle without having the key to the lock.

Having thus described the invention, what 20 I claim as new and desire to secure by Letters Patent, is:—

A poison bottle guard, including a spring 25 clip adapted to fit around the bottle neck, a stock projecting upwardly from the spring

clip, said stock being laterally offset at an intermediate point in its length to form a shoulder adapted to fit against and engage the exterior bead at the mouth of the bottle neck to prevent the spring clip from sliding upwardly on the bottle neck, a spring finger projecting laterally from the upper end of the stock and adapted to fit over the stopper to retain the same in position within the bottle neck, prongs projecting from the 35 spring finger and adapted to bite into and embed themselves in the stopper, and a lip projecting downwardly from the outer end of the spring finger for engagement with the side of the stopper to hold the poison 40 guard against accidental displacement from the bottle.

In testimony whereof I have signed my name to this specification in the presence of two subscribing witnesses.

EARL DENNY.

Witnesses:

E. H. JOLLIFFE,
GERTRUDE PHILLIP.
